US0D1032263S

(12) **United States Design Patent** (10) **Patent No.:** **US D1,032,263 S**
(45) **Date of Patent:** **** Jun. 25, 2024**

(54) **RETAIL FIXTURE**

(71) Applicant: **Apple Inc.**, Cupertino, CA (US)

(72) Inventors: **Allison Inouye**, San Francisco, CA (US); **Jean-Marc Gady**, Los Altos, CA (US); **Ismael Flores Trujano**, San Jose, CA (US); **Gregory Guillaume Lespinard**, San Jose, CA (US); **Mike Zou**, San Francisco, CA (US); **Po Huang**, San Jose, CA (US); **Wesley Bryan Hamm**, San Francisco, CA (US); **Russell John Kaaihue Heirakuji**, Cupertino, CA (US); **Joshua Robert Edwards**, Santa Cruz, CA (US); **Nicholas E. Corti**, San Francisco, CA (US); **Manuel Dejesus**, San Francisco, CA (US); **Alice Marlin Brugger**, San Francisco, CA (US)

(73) Assignee: **Apple Inc.**, Cupertino, CA (US)

(**) Term: **15 Years**

(21) Appl. No.: **29/828,292**

(22) Filed: **Feb. 25, 2022**

Related U.S. Application Data

(63) Continuation of application No. 29/713,507, filed on Nov. 15, 2019, now Pat. No. Des. 946,325.

(57) **CLAIM**

The ornamental design for a retail fixture, as shown and described.

DESCRIPTION

FIG. 1 is a top front perspective view of a retail fixture showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

(Continued)

The broken lines in the figures show portions of the retail fixture that form no part of the claimed design.

1 Claim, 4 Drawing Sheets
